UNITED STATES PATENT OFFICE

PAUL A. BANCEL, OF NEW YORK, N. Y.

BOILER.

1,225,304.

Specification of Letters Patent.

Patented May 8, 1917.

Application filed July 9, 1913. Serial No. 778,034.

To all whom it may concern:

Be it known that I, PAUL A. BANCEL, a citizen of the United States, residing at New York city, county and State of New York, have invented certain new and useful Improvements in Boilers, of which the following is a full, clear, and exact description.

The invention which constitutes the subject matter of this application relates to boilers.

It is a matter of common knowledge that the bottom tubes of horizontal water tube boilers have a tendency to burn out under heavy loads. This proves that the amount of heat to be absorbed becomes very great and that the circulation in the bottom tubes is not fast enough to supply sufficient water for evaporation. Or, stated in another way, the percentage of steam in the mixture discharged from the lower nest of tubes is very great, as compared to the percentage of steam in the mixture discharged from the upper nest of tubes. Experiments and theory indicate that the first row of boiler tubes directly over the fire is doing something like 35% to 40% of the work done by the whole of ten rows; that the second row is doing 15% to 20% of the work; and the fifth, for instance, but little more than five per cent of the work.

The rapidity of circulation in a boiler tube is controlled, among other things, by the difference in weight of the column of fluid at the entrance and discharge of any tube. My invention relates to an approved form of boiler for segregating the mixture from the lower group or nest of tubes from groups or nests of tubes higher up, so as to obtain maximum rapidity of circulation in the bottom tubes.

The invention consists further in so constructing the boiler that the water fed to the bottom tubes of the boiler can be only such water as has already passed through the upper tubes, and is partly purified by the action of the heat in these tubes.

Other advantages and objects of my invention will appear from the detailed description given below, in connection with the accompanying drawings, which show preferred embodiments of the invention and in which—

Figure 1 shows a longitudinal vertical section taken on the line *a—b* of Fig. 2.

Fig. 2 is a cross-section taken on the line *c—d* of Fig. 1.

Fig. 3 is a top plan view of the feed pipe and associated mechanism.

Fig. 4 is a section similar to that shown in Fig. 2, illustrating my invention in conjunction with a boiler provided with a plurality of drums.

Fig. 5 is a section on line *e—f* of Fig. 6 illustrating the invention as applied to an A-shaped boiler.

Fig. 6 is a horizontal section on line *g—h* of Fig. 5.

The simplest application of the invention is shown in Figs. 1 and 2. In detail, 10 indicates the water and steam drum, 11 the front header, 12 the rear header, 13 the boiler tubes, of one of the conventional types of Heine boiler. For the sake of simplicity the furnace and setting are omitted.

The front header is provided with a light sheet iron partition 14 which forms two separate channels 15 and 16 at the left and right for the direct flow of steam and water from the bottom rows of tubes to the drum.

To provide this additional space, the boiler tubes, in the preferred construction, are not spaced out the full width of the header; in other words, the header is made somewhat wider than is needed for the width of the tubes, and as a result it enables me to connect the lower tubes, in which the greatest evaporation takes place, independently with the steam drum, and as the discharge from these tubes contains a large proportion of steam the weight of the column of steam and water between these tubes and drums is correspondingly light and the circulation brisk. The partition 14 also provides a separate channel 17 through which the steam and water flow from the upper boiler tubes to the steam and water drum.

The rear header 12 is provided with a partition member 19, which is employed in co-operation with other novel structures in the boiler drum, so that only water that has been already fed to the upper tubes can be fed to the lower tubes. As a result, all water that is fed to the lower tubes has been partially purified by its passage through the upper tubes. This partition 19 divides the rear header into three separate channels 20, 21 and 22, see Fig. 3. Ordinarily, it would be unnecessary to put partitions in the rear header similar to those in the front header,

since the area for the downward flow of water in the rear water leg is ample to insure a good supply of water to the bottom tubes as well as to the upper tubes. However, by inserting a partition or partitions in the rear header similar to those in the front header, an advantage of another nature, as stated above, is secured. Within the drum 10 is a feed water pipe 23, so directed that the water discharged therefrom, instead of being admitted to mix with all the water in the main steam drum and then to flow partly to the upper tubes and partly to the lower tubes of the boiler, is constrained to flow downward into the central channel or passage-way 22 of the water leg which connects only with the upper tubes of the boiler. The water rising from the front header flows back through the drum, and at the rear it flows down the rear header not only in the outer parts communicating with the lower tubes, but also in the central part communicating with the upper tubes, mixing with the fresh feed. The novel construction and location of the feed water pipe together with the partitioned header (rear) simply insures that the feed water discharged from the feed-pipe cannot pass directly to the tubes nearest the fire.

30. In Fig. 4 I have illustrated the invention wherein a plurality of drums are employed. In this case the partition plates 24 and 25 divide the header into five channels, namely 26, 27 and 28, for the passage of steam and water from the lower tubes to the drums and 29 and 30 for the passage of steam and water from the upper tubes to the drums.

In Figs. 5 and 6, I show the manner of utilizing the invention broadly with a modified form of boiler construction. The headers in this figure are of wedge-shaped construction. The tubes 31 and 32 are nearest the furnace and are most liable to be burnt out, and are provided with separate channels or flues 33 and 34 respectively of comparatively large area for the separate flow of the discharge directly to the drum. The tubes 35 and 36, which form the remainder of the roof of the combustion chamber, discharge into the separate channels or flues 37 and 38, respectively. The inclination of the tube is such that the steam and water discharged from them make an easy turn upward into the flue and as a result there is maintained superior flow and circulation in them. This modified form of header also carries with it this important advantage, among others, that an A-shaped combustion chamber is obtained. Owing to the wedge-shape construction of the passes 39 and 40 the rear end of the baffles 41 and 42 are arranged on a bias, as indicated at 43 and 44 in order to effect a uniform absorption of heat throughout the

boiler tubes located in these passes. The angle which the ends of the baffles make with a longitudinal line depends largely upon the inclination of the lower tubes.

It will be noted that the channels in the front header for the lower nest of tubes are provided with box-like extensions 45 within the boiler drum which project above the water line α . See particularly Fig. 1. This allows a free and unobstructed passage for the flow of water and steam from the lower nest of tubes to the drum. Or stated in other words, they maintain the weight of the mixture of water and steam in the corresponding channels at a minimum. The passageways or channels 15 and 16, together with the box extensions 45 constitute in effect a conduit for the flow of steam and water from the boiler tubes to the boiler drum, the portions or extensions 45 serving to effect the liberation of steam from the passageways or channels.

It is to be understood that I do not limit myself to the exact details of construction herein shown, and described, as minor changes may be made and other embodiments resorted to without necessarily deviating from the true spirit and scope of my invention.

What I claim is—

1. A header or water leg for water tube boilers, provided with a separate passageway within the same to convey the steam and water from the lower tubes directly to the water and steam drum, and formed by a partition or partitions normal to the plane of the header. 95
2. A header or water leg for water tube boilers, provided with a plurality of passageways within the same, each of said passageways adapted to convey steam and water from groups or nests of tubes located at different heights, said passageways formed by partitions normal to the plane of the header. 105
3. A water tube boiler comprising front and rear headers, each divided into a plurality of passageways, the upper nest of boiler tubes connected to one of the passageways of each of said headers and the lower nest of tubes connected to another passageway in each of said headers, and means for admitting feed water through the upper nest of tubes and its corresponding passageway to the water and steam drum, said passageways in said headers for the lower nest of tubes connecting directly with the drum whereby the water from said drum previously heated by passing through the upper tubes is permitted to circulate through the lower nest of tubes and the last mentioned passageways. 115
4. A water tube boiler provided with means for admitting only water to the lower nest of tubes which has already passed through the upper nest of tubes, comprising 120

a front and rear header provided with passageways to which the upper tubes are connected and separated passageways opening into the water and steam drum to which the lower tubes are connected, and means for admitting feed water to the drum through the upper tubes and connected passageways.

5. A water tube boiler provided with means for admitting only water to the lower nest of tubes which has already passed through the upper nest of tubes, comprising front and rear headers each provided with a passageway leading to and from the drum respectively and to which the upper tubes are connected, and separated passageways opening into the water and steam drum to which the lower tubes are connected, and means for admitting feed water to the boiler and steam drum through the upper tubes and its connected passageways, said last mentioned passageways opening directly into the steam drum whereby water from said drum is adapted to circulate through said upper nest of tubes in addition to the flow from the feed pipe.

6. The combination with a water tube boiler, of a furnace in which the water tubes are disposed to form an A-shaped combustion chamber in a plane at right angles to the tubes, with means for segregating the steam and water discharged from the tubes of the boiler, so that the discharge from the tubes nearest the furnace flows to the steam and water drum without mixing with the discharge from the tubes more remote from the furnace.

7. The combination with a water tube boiler, of a furnace in which the water tubes are disposed to form an A-shaped combustion chamber in a plane at right angles to the tubes and also forming wedge-shaped passes for said furnace gases, and baffles located in said boiler with the ends thereof cut on a bias to effect a uniform absorption of heat throughout the boiler tubes in said passes.

8. The combination with a water tube boiler, of a furnace in which the water tubes are disposed to form an A-shaped combustion chamber in a plane at substantially right angles to the tubes and also forming wedge-shaped passes for said furnace gases, and means for admitting water to the lower nests of tubes which has already passed through the upper nests of tubes comprising front and rear headers provided with passageways to which the upper tubes are connected, and separated passageways opening into the water and steam drums to which the lower tubes are connected, and means for admitting feed water to the drums through the upper tubes and connected passageways.

9. The combination with a water tube boiler of a furnace in which the water tubes are disposed to form an A-shaped combustion

chamber in a plane at substantially right angles to the tubes and also forming wedge-shaped passes for said furnace gases, baffles located in said boiler with the ends thereof cut on a bias to effect a uniform absorption of heat throughout the boiler tubes in said passes, means for admitting water to the lower nests of tubes which has already passed through the upper nest of tubes comprising front and rear headers provided with passage-ways to which the upper tubes are connected, and separated passage-ways opening into the water and steam drums to which the lower tubes are connected, and means for admitting feed water to the drums through the upper tubes and connected passage-ways.

10. The combination with a water - tube boiler provided with a plurality of horizontal drums of a furnace in which the water tubes are disposed to form an A-shaped combustion chamber in a plane at substantially right angles to the tubes, and means for segregating the steam and water discharged from the tubes of the boiler comprising front and rear headers provided with passage-ways to which the upper tubes are connected, and separated passage-ways opening into the water and steam drums to which the lower tubes are connected, and means for admitting feed water to the drums through the upper tubes and connected passage-ways.

11. The combination with a water - tube boiler provided with a plurality of horizontal drums, of means for admitting only water to the lower nests of tubes which has already passed through the upper nests of tubes comprising a front and a rear header provided with passage-ways to which the upper nests of tubes are connected, and separated passage-ways opening into the water and steam drums to which the lower nests of tubes are connected, and means for admitting feed water to said drums through the upper nests of tubes and connected passage-ways.

12. The combination with a water - tube boiler provided with a plurality of horizontal drums, of means for admitting only water to the lower nests of tubes which has already passed through the upper nests of tubes comprising a front and a rear header each of which is common to said plurality of drums and each of which is provided with a plurality of passage-ways to which the upper nests of tubes are connected, and separated passage-ways in each of said headers opening into the water and steam drums to which the lower nests of tubes are connected, and means for admitting feed water to each of said drums through the upper nests of tubes and connected passage-ways.

13. A header or water-leg for water-tube boilers provided with a separate passageway within the same to convey the steam and water from the lower tubes to the water and

steam drums, said passageway formed by a partition normal to the plane of the header, in combination with means for effecting a separate liberation of steam discharged from each of said lower tubes.

14. A header or water-leg for water-tube boilers provided with a plurality of passageways within the same, each of said passageways adapted to convey steam and water from groups or nests of tubes located at different heights, said passageways formed by

partitions normal to the plane of the header, in combination with means for effecting a separate liberation of steam discharged from each of said passageways.

In testimony whereof I affix my signature in the presence of two subscribing witnesses.

PAUL A. BANCEL.
